UNITED STATES PATENT OFFICE.

JULIUS H. HOLMGREEN, OF SAN ANTONIO, TEXAS.

PRESS.

SPECIFICATION forming part of Letters Patent No. 335,816, dated February 9, 1886.

Application filed May 7, 1885. Serial No. 164,667. (No model.)

To all whom it may concern:

Be it known that I, JULIUS H. HOLMGREEN, of San Antonio, in the county of Bexar and State of Texas, have invented a new and Improved Press, of which the following is a full, clear, and exact description.

The object of my invention is to facilitate the baling of cotton and other fibrous substances.

10 The invention consists in compressing-rollers placed in suitable bearings, so as to coincide with an inlet-channel which receives and guides the fibrous substance to be baled into the baling-box of a press after the compressing-rollers have given it a preparatory pressing.

The invention further consists in details and combinations of parts, as will hereinafter be fully described and claimed.

20 Figure 1 is a sectional view through the lines x x of Fig. 2. Fig. 2 is an end view of the press, and Fig. 3 is a detail cross-sectional view of the compressing-rollers.

In the drawings, A represents the baling-box of the press, which rests upon the supporting-timbers A', which are in turn supported by the ground-timbers A''. The upper timbers, B', which rest upon the shoulder B' of the tie-bolt B'', are parallel with the timbers A'. The tie-bolts B'' unite the upper and lower timbers, thereby making a firm and strong frame-work for holding the different parts of the press in position.

30 The baling-box A has its side walls hinged at their bottoms to battens a' on the timbers A'', to facilitate the removal of the baled material after being properly strapped. The baling-straps used for this purpose are held in the spaces intervening between the floor-slats a'' of the box A and the slats a''' on the follower B. To the follower B, which works in the baling-box A, is secured, by means of the bolt c', the piston C, working in the hydraulic cylinder D. The cylinder has lugs e, which are secured to the cross-timbers b b' by the bolts e', thereby holding the cylinder firmly in position. At the top of cylinder D a pressure-gage, E, is attached, and leading from the top of cylinder D to the water-tank G, which is held in position by the side projection, g, being secured to the timbers B', is the exhaust-

pipe F, having suitable stop-cock, H, for exhausting the water in the hydraulic cylinder D when it is desired to raise the follower B. The pipe J, which connects the pump I with the cylinder D, has a branch pipe, j, which leads to the tank for supplying the water for operating the piston C.

55 The eccentric-rod i', which reciprocates the piston-rod i'' of the pump I, through the medium of the eccentric K on the shaft L, plays horizontally in the guide i'', which projects downward from the bar b'' on the timbers B''. This holds the rod i' against lateral movement. The forward stroke of the pump-piston draws 60 the water from the tank G through the pipe j into the pipe J, and the return-stroke of the pump-rod closes the valve d, opens valve d', and forces the water through the pipe J into the cylinder D, where it acts on the piston C, 65 causing the follower B to descend within the baling-box A. The eccentric K on the shaft L, which reciprocates the pump-piston i'', receives its motion from pinion N', which is loosely mounted on the shaft O, meshing with 70 the gear-wheel N' on the shaft L. To the outer end of the shaft O the driving-pulley P is secured, and on the shaft O a gear-wheel, Q, is loosely mounted, which meshes with the gear-wheel q on the roller S, and the pinion s on 75 the opposite end of roller S revolves the roller R by meshing with its pinion r. By this train of gearing motion is communicated to the pump and compressing-rollers S and R, and as it is necessary to work the compressing-rollers R and S first independently of the pump 80 a double clutch, p, is feathered on the shaft O between the gears N' and Q. The clutch p is shifted to engage with clutches formed on the opposite faces of the pinions N and Q by 85 means of a forked lever working in the annular groove p'.

90 The compressing-rollers R and S are journaled in adjustable bearings w in the box T, which are adjusted and held down by the springs u. The side of the box T joining the feeding-apron W is open, and on the opposite side of the box T a guiding inlet-channel, t, having its inner end beveled to fit against the rollers, is situated, the object of which is to 95 receive the material to be baled from the preparatory rollers R and S and deliver it to 100

the baling-box A. It also prevents the material from winding around the rollers R and S.

In operating the press the pump is thrown out of action by shifting the clutch *p* to engage 5 with the gear Q and to be out of engagement with the pinion N'. The pinion N', by being loosely mounted on the shaft O, receives no motion from said shaft, and consequently the pump is at rest. The gear Q being engaged 10 with the feathered clutch *p* is caused to revolve, and by meshing with the pinion *q* the motion is imparted to the roller S, and through pinions *s* and *r* to the roller R. The material to be baled is now fed down the apron W to the 15 rollers R and S, between which it receives a preparatory compressing, and then is forced by the said rollers into and through the inlet-channel *t* to the baling-box. When the desired quantity has been fed to the baling-box, 20 the clutch *p* is shifted, which stops the rollers R and S and operates the pump I by the motion imparted to the eccentric K by the gears N' and N. The pump I drawing water from the tank G and forcing it into the cylinder D, 25 as before described, causes the follower B to descend within the baling-box A, and gives the material the final packing in the baling-box, after which the side walls are swung down and the baling-straps adjusted, when the bale is 30 removed.

Although I have here shown a hydraulic press, it is evident that the preparatory compressing-rollers R and S may be used in connection with any form of press with great ad- 35 vantages, as by the use of the rollers R and S the

large unwieldy press-box now in common use is discarded and a smaller and more easily-managed one substituted, taking up less room and enabling the attendant to work and control a number of presses at the same time.

40

Having thus described my invention, what I claim as new, and desire to secure by Letters Patent, is—

1. In a baling-press, the combination, with 45 the baling-chamber having in one side or wall an inlet or feeding channel, of the follower, the feed-hopper, and the compressing-rollers arranged at the lower end of said hopper, and with the feed-passage between them in alignment with the feeding or inlet channel, which 50 channel also extends to the compressing-rolls, substantially as and for the purpose set forth.

2. In a baling-press, the combination, with 55 the box A, of the rollers R and S, the box T, the journal-boxes *w*, the spring *u*, the inlet-channel *t*, extending outward from the inner wall of the box T to the rollers R and S, and of the apron W, substantially as herein shown and described.

3. In a baling-press, the combination, with 60 the pump I, operating the hydraulic piston C, and follower B, of the gear-wheels N N', the clutch *p*, the gear-wheels Q *q*, and the compressing-rollers R and S, substantially as herein shown and described.

JULIUS H. HOLMGREEN.
